Attorneys

UNITED STATES PATENT OFFICE.

THOMAS E. ROBINSON, OF TULSA, OKLAHOMA.

CASING CLAMP.

Application filed October 6, 1923. Serial No. 666,976.

To all whom it may concern:

Be it known that I, THOMAS E. ROBINSON, a citizen of the United States, residing at Tulsa, in the county of Tulsa and State 5 of Oklahoma, have invented certain new and useful Improvements in Casing Clamps, of which the following is a specification.

My invention relates generally to oil well apparatus and in particular to well casing 10 clamps. Objects thereof are: a separable clamp for supporting and holding a well casing, the component parts thereof being secured by interlocking engagement; a clamp of this character adapted to engage 15 a casing at any point; a clamp provided with insertable casing gripping means, and means to prevent spreading of the clamp when supporting a casing. Other objects will be apparent from the description.

20 The details of the invention reside in the novel construction, combination and arrangement of parts hereinafter described and claimed, and illustrated in the accompanying drawings, of which;

25 Figure 1 is a top plan view of the clamp as applied,

Figure 2, a side elevation thereof, partly broken away,

30 Figure 3, an end view, with part broken away for illustration of detail.

The details of the clamp comprise a base 35 consisting of two separable and interlocking side members 1 and 2. Each side member is identical in construction, for interchangeability, and the central portion of the base, where the casing gripping means is positioned, is of a greater height than at its ends, to provide a thickened portion for insuring greater strength. From the center to each end, the upper faces of each side member are downwardly inclined, while their bottom faces are horizontal, providing a flat bottom for the base.

40 The central portion of each side member is provided with a semicircular bore so that when in assembled position, the base will surround a well casing section 3. The face of each semicircular bore or recess is tapered downwardly for wedging engagement with a reversely tapered semicircular clamping plate 4 and 5, provided with serrated inner 45 faces 6 for gripping engagement with the casing section when applied.

To each wedge plate 4 and 5 is suitably

secured a handle 7 whereby the plate may 55 be lifted from engagement with the base, and displacement of the plates with respect to the side members is prevented by engagement of dovetailed lugs 8 and 9 on the back of each plate respectively, in dove-tailed sockets 10 and 11 in the respective side members 1 and 2 at diametrically opposed points. The bottom of each socket is closed to prevent the plates from slipping down within the central bore of the 65 base.

Between the outer ends and the central portion, each side member 1 and 2 of the base is curved outwardly in bell shaped formation on its outer wall, while the abutting inner walls are arranged for interlocking engagement. The member 1 carries two lateral extensions or shanks 12 and 13 on opposite sides of the central portion, which project beyond the median line 75 of the base and terminate in knuckles 14 and 15 extending in the same direction. The side member 2 is of exact counterpart formation with reversely arranged shanks 16 and 17 and knuckles 18 and 19. The respective knuckles overlap and interlock, 80 effectually joining the base members and preventing spreading thereof. The meeting walls of the side members at opposite sides of the central portion are arranged on 85 opposite sides of the median line of the base, as shown in Figure 1, thus providing stronger shanks 13 and 17, than would otherwise be the case.

The clamp is designed to be used at the 90 top of a well and in operation one side member is placed in position with its ends resting on suitable supports. The other side member is then applied from the opposite side of the well casing and nested 95 within the first for interlocking engagement of the members around the well casing. The wedge plates are then inserted within the base and the downward pull of the casing will be taken up by the base and the casing held at the desired point. With this construction the casing may be retained at any point irrespective of the coupling on each section.

While certain details have been illustrated and described I desire it to be understood that the invention is not limited to such, but that any changes and modifica-

tions may be made in the details and arrangement as will fall within the scope of the invention as claimed.

I claim:

- 6 1. A casing clamp for oil wells comprising a base formed of two equal size members having their intermediate portions adapted to surround an oil well casing, interlocking overlapping knuckles integrally formed on the inner walls of said members and adapted for cooperative engagement at diametrically opposite points with respect to the casing to form the sole means for securing the base members in assembled 10 position.
- 10 2. A casing clamp for oil wells comprising a base formed of two equal size members having their intermediate portions adapted to surround an oil well casing, laterally and inwardly extending shanks on the inner walls of said members, knuckles on said shanks adapted for overlapping and interlocking engagement, and the meeting walls of the base members adjacent the central portions being arranged on opposite sides of the median line of the assembled base.

In testimony whereof I affix my signature.

THOMAS E. ROBINSON.
